NO. 13,428

NOVEMBER 14, 1882

UNITED STATES PATENT OFFICE

JOHN L. POPE, OF CLEVELAND, OHIO.

DESIGN FOR A CARRIAGE-STEP.

SPECIFICATION forming part of Design No. 13,428, dated November 14, 1882.

Application filed August 2, 1882. Term of patent 14 years.

To all whom it may concern:

Be it known that I, JOHN L. POPE, of Cleveland, in the county of Cuyahoga and State of Ohio, have invented and produced a new and original Design for Carriage-Steps, of which the following is a specification, reference being had to the accompanying photographic illustration, forming part thereof.

My invention relates to a new design for carriage-steps; and it consists in the ribbed ornamentation shown, and to be hereinafter more particularly described.

In the accompanying photograph the center figure of the step is composed, as shown, of ribbed or raised work, and has the appearance of a quarterfoil with a cross, *b*, in the middle. This figure is produced by the employment of two incomplete ellipses, *a c*, oppositely disposed, and a ribbed cross joined thereto. Near each of the four corners of the plate, and running obliquely thereof, will be seen a large partially-formed elliptical-shaped figure, *d*, of ribbed work, the same in outline as either of those marked *a c*. On account of the direc-

tion in which the figures *d* are laid out, the crosses *b'* appear to be X-shaped, when viewed perpendicularly to the sides of the step. At each corner of the plate I have placed an additional ornament of ribbed work, triangular-like in contour, and have marked it with the letter *e*.

The openings between the various figures are not essential to the novelty of my design, the gist of which lies in the ornamental ribbed work disposed as described.

What I claim as my invention, and desire to secure by Letters Patent, is—

A new design for a carriage-step plate, consisting of the ribbed central figure, *a b c*, and the surrounding raised figures *b' d*, with or without the figure *e*, substantially as shown.

In witness whereof I have hereunto set my hand this 31st day of May, 1882.

JOHN L. POPE.

In presence of—

A. A. POPE,
C. M. COPP.
